9 Claims. (Cl. 72—138)

The present invention relates to the manufacture of helical coils of wire, these coils being inclined relative to the axis of winding so as to overlap each other and being offset from each other so that they are partially separated in two opposite zones and partially contiguous in two zones in which they cross each other.

The object of the invention is to provide a method of continuously manufacturing such windings, this method comprising continuously bending the wire at a periodically variable radius of curvature.

Another object of the invention is to provide a device for carrying out said method and comprising, following on means which feed the wire and include feed pulleys at least one of which is a driving pulley, two support rollers which face each other and a bending roller whose eccentric axis of rotation is offset relative to the path in which the wire is fed between the support rollers.

This method and device are remarkably simple and permit a high rate of manufacture of helical windings of wire having offset coils with low power consumption.

Further features and advantages of the invention will be apparent from the ensuing description, with reference to the accompanying drawings to which the invention is in no way limited.

In the drawings:

FIGURE 1 is an elevational view of the device for manufacturing a helical winding of metal wire having offset coils;

FIGURE 2 is a view taken along line 2—2 of FIGURE 1;

FIGURES 3 and 3a are partial detail views corresponding to FIGURE 2, showing the bending and formation of the first aligned coils of wire;

FIGURES 4 and 4a are views similar to FIGURES 3 and 3a showing a modification in the spacing or offsetting of the coils;

FIGURES 5 and 5a are similar views showing a modification in the diameter of the coils with a straight axial line of winding;

FIGURES 6, 6a and 7 are similar views showing a modification in the diameter of the coils with a curved axial line of winding, and

FIGURE 7 is a detail elevational view corresponding to FIGURE 6 and showing the formation of a winding of coils the planes of which are inclined relative to each other.

In the embodiment shown in FIGURES 1 and 2, the device according to the invention is adapted to wind or coil a metal wire F, fed by a reel B, into helical coils which are offset from each other and oblique relative to the axial line of winding.

This device comprises a horizontal table 1 on which are mounted the feed means for the wire F and the means for winding this wire.

The feed means comprise two pulleys 2, 3 which have vertical axes and feed the wire F in a horizontal direction. These pulleys are in facing relation with one another. Their spindles are journaled in bearings carried by the table 1. One of the pulleys, 2 for example, is a driving pulley and is driven in rotation by a motor 4. Following on the feed pulleys and located in the same horizontal

2

plane, is a pair of support rollers 5, 6 which are in facing relation with one another, are rotatively mounted on vertical spindles carried by the table 1, and form therebetween a passage for the wire F.

The winding means comprise a bending roller 7 which is in the same horizontal plane as the rollers 5 and 6 but offset from the latter. The roller 7 is in the form of a disc which has a diameter D and a vertical spindle 8 journaled in the horizontal table 1 through the medium of a bearing 9. Its vertical axis of rotation X—X is eccentric to the extent of the distance e relative to its center O. The position of the axis of rotation X—X of the bending roller 7 is defined relative to the axis of one of the support rollers (for example roller 5) by the dimensions x and y (FIGURE 3). These distances can be made adjustable, for example by mounting the bearing 9 on the table 1 through the medium of a transverse carriage 10 and a longitudinal carriage 11 which are diagrammatically represented in FIGURE 1.

The bending roller 7 can for example comprise a part-circular groove for receiving the wire F.

The device operates in the following manner:

After the metal wire F has been introduced between the feed pulleys 2, 3, the motor 4 is started up. The driving pulley 2 feeds the wire F to the point a between the support rollers 5, 6 and then against the bending roller 7 which deviates the wire from its direction of feed (FIGURES 2 and 3). Consequently, the roller 7 bends the steel wire F into a curved shape having a radius of curvature r, this curved wire being tangent to the roller 7 at t (FIGURE 3). The radius of curvature r depends on the position of the point t relative to the point a of passage between the rollers 5 and 6. As it is fed forward, the wire F in tangential contact at t with the bending roller 7, drives the latter in rotation. At each instant the position of the point t therefore varies as a function of the radius of the bending roller measured between the axis X—X and said point t. In FIGURE 3 the radius of the bending roller at point t has a substantially minimum value. In travelling round the circumference of the eccentric roller 7, the radius measured between the axis X—X and the point t passes through a minimum value, progressively increases up to a maximum value and then once more decreases. This is due to the eccentricity e of the roller 7. The point t therefore moves toward the rollers 5, 6 when the radius of the bending roller 7 at the point t is maximum (minimum radius r of curvature of the wire), then moves away from the rollers 5, 6 when the radius of the bending roller increases. Consequently the radius of curvature r of the bent wire decreases then increases. As a result of its curvature, which varies during a complete rotation of the bending roller, the wire F is wound into a coil having the shape of a "6" from the point b to the point c (FIGURES 2 and 3a). Thus, the following coil is formed with an offset p relative to the first coil. The coils have an outside diameter E.

It should be noted that during the bending for forming the second coil, the first coil formed turns about the variable center of curvature of the second coil being formed. When a third coil is being formed, the first two coils formed turn in the same manner about the variable center of curvature of the third coil being formed.

The winding of the coils can assume different shapes and dimensions in accordance with the dimensions and position of the bending roller 7.

A few factors will now be examined.

(1) Winding along a straight axis (FIGURES 1, 2, 3, 3a, 4, 4a, 5, 5a)

The formed coils are aligned on a straight axial line of winding Y—Y if the device is set by means of the

carriages 10 and 11 (FIGURE 1) so that the bending roller 7 is disposed at a distance x from the support rollers 5, 6 and the coils formed have a perimeter measured between the points b and c which is equal to that of the bending roller 7. Indeed, if this condition is satisfied, each coil is formed in accordance with a shape of a "6" during one complete rotation of the bending roller 7 about the axis X—X. In other words, the period of winding of each coil is equal to the period of a complete rotation of the bending roller. All the coils are therefore formed with curvatures which are reproduced in identical manner for each rotation of the roller with an offset in translation p so that they are aligned on the axis Y—Y.

(2) *Variation in the offset between the coils as a function of the eccentricity of the bending roller (FIGURES 4, 4a)*

As has just been explained, the offset of the coils of constant value p is due to the eccentricity e of the bending roller 7. Consequently if a bending roller 7a having the same diameter D but an eccentricity e_1 is used, the amplitude of the variation in the radius of this roller, measured between the axis X—X and the point t_1 , decreases. The same is true in respect of the amplitude of the variations in the radius of curvature r of the coils and therefore of the offset p_1 of the coils. In the extreme case, if the eccentricity e_1 of the bending roller 7a is zero, the offset p_1 is also zero and a helical winding having contiguous circular coils is produced. On the other hand, in increasing the eccentricity the offset p_1 also increases. In the other extreme case, if the eccentricity e_1 of the bending roller 7a is equal to its radius measured from its center O, the offset p_1 is very large and the loop in the "6" formed is very squashed so that the winding obtained resembles a series of arches.

(3) *Outside diameter of the coils (FIGURES 5 and 5a)*

It has been seen that the radius r of curvature of the coils increases when the point of contact t with the bending roller moves away from the support rollers 5, 6 and decreases when the point t moves toward these rollers. Thus, if the roller 7 is placed at a distance x_1 from the rollers 5, 6 that exceeds the distance x (FIGURE 3), the outside diameter of the coils has a value E_1 that exceeds the value E . Inversely, if the distance x_1 between the bending roller and the support rollers 5, 6 is less than x the outside diameter of the coils is less than E .

It should be noted that to obtain a winding along a straight axial line Y—Y, it is necessary to change the bending roller and adopt a roller 7b having a diameter D_1 whose perimeter is equal to that of the new coils. It is indeed necessary that the period of a complete rotation of the bending roller be equal to the period of winding of a complete coil. Consequently, if the outside diameter of the coils is increased from E to E_1 , the diameter of the bending roller must be increased from D to D_1 and vice versa.

If the offset of the coils having diameter E_1 must have the same value p as that of the coils having diameter E , the eccentricity of the new bending roller 7b having a diameter D_1 must have a value e' corresponding to the modification in the diameter of the roller.

(4) *Winding along a curved winding axis line (FIGURES 6 and 6a)*

It has been seen that the straight axial line of winding Y—Y is obtained with a bending roller 7, 7a or 7b whose perimeter is equal to that of the coils. If the perimeter of the roller 7 having a diameter D is less than that of the coils having a diameter E_2 (FIGURE 6)—which is obtained by a suitable adjustment of the radius of curvature, namely the distance x_2 —the period of a complete rotation of the bending roller 7 is less than the period of winding of a complete coil. In other

words, after one complete rotation of the bending roller 7, the coil is not yet complete. It is only completely formed between the points b and c when the bending roller 7 has effected a little more than a complete rotation. If the coil is compared to the shape of a "6," the loop of the 6 is closed to a greater extent than in the case of the straight axial line Y—Y. Consequently, the start of the curve of the following coil does not have the same radius as the start of the first coil. Indeed, the homologous points of the successive coils, that is, the points at which the successive coils have identical curvatures, are displaced relative to each other in accordance with rotational movement so that the coils have a curved outside envelope in the form of a portion of a ring having an axis $Y_1—Y_1$. With a sufficient number of coils, a complete ring can thus be formed. This winding curves toward the right in the case of FIGURE 6 in which the perimeter of the bending roller is less than the perimeter of each coil. In the opposite case shown in FIGURE 6a, wherein the perimeter of the bending roller 7 is greater than that of the coils having a diameter E_2 —owing to a positioning of this roller at a distance x_2 from the rollers 5, 6 which is less than the distance x —the winding curves toward the left. Indeed, the period of a complete rotation of the bending roller is no longer less but greater than the period of winding of a coil. As before, the coils are therefore displaced relative to each other in accordance with the rotational movement but in the opposite direction.

(5) *Planes of the coils inclined relative to each other (FIGURE 7)*

In upwardly displacing or offsetting the plane of the bending roller 7 relative to the plane in which the wire F is fed, there is produced, in addition to the aforementioned bending, an inflection of the coils and the latter issue from the device in inclined relation with each other. In this way, a winding is obtained having a curved axial line $Y_3—Y_3$ whose outside envelope (shown in dotted line) is in the shape of a torus.

Although specific embodiments of the invention have been described, many modifications and changes may be made therein without departing from the scope of the invention as defined in the appended claims.

Thus, instead of driving the bending roller in rotation through the medium of the wire to the bent—which is in tangential contact therewith—a positive drive could be provided for this bending roller by a mechanism driven with a suitable transmission ratio by the motor 4. Further, instead of placing the bending roller 7 on the downstream side of the support rollers 5, 6, it could be placed on the upstream side thereof, between these rollers and the feed rollers 2, 3. In the case of the embodiment shown in FIGURE 7, to obtain a winding on a curved axial line $Y_3—Y_3$ and having a toric envelope, the bending roller 7 could be inclined relative to the plane in which the wire F is fed. It should be noted that the bending roller can be cylindrical and smooth, that is, without a groove.

Having now described my invention what I claim as new and desired to secure by Letters Patent is:

1. A device for obtaining a helical winding of a metal wire, which winding comprises coils that are inclined relative to the axis of winding and offset from each other, said device comprising means for feeding the wire longitudinally, two support rollers which are in facing relation to each other on both sides of the wire fed by the feeding means, and a rotary bending roller having an axis of rotation which is located within the bending roller and is eccentric relative to the center of the bending roller and offset in a fixed position relative to the path in which the wire is fed by the feeding means between the support rollers, the support rollers and said axis of rotation being so located relative to each other that the feeding means and support rollers feed the wire against the periphery

of the bending roller so that the wire is bent thereby, the radius of curvature of the bend produced in the wire being a function of the radial distance between the point of contact of the wire on the periphery of the bending roller and said axis, said distance varying progressively as the bending roller rotates about said axis as the bending of the wire proceeds.

2. A device as claimed in claim 1, wherein the distance between the axis of rotation of the bending roller and the axis of rotation of one of the support rollers is adjustable so as to regulate the curvature of bending and consequently the outside diameter of the coils.

3. A device as claimed in claim 1, wherein the bending roller is detachable and interchangeable.

4. A device as claimed in claim 1, wherein the bending roller is driven in rotation by the frictional contact between the wire and the bending roller.

5. A device as claimed in claim 1, wherein the feeding means comprise feed rollers engaging the wire, the device further comprising a motor which drives in rotation one of the feed rollers and the bending roller.

6. A device for obtaining a helical winding of a metal wire, which winding comprises coils that are inclined relative to the axis of winding and offset from each other, said device comprising means for feeding the wire longitudinally, two support rollers which are in facing relation to each other on both sides of the wire fed by the feeding means, and a rotary bending roller having an axis of rotation which is located within the bending roller and is eccentric relative to the center of the bending roller and offset in a fixed position relative to the path in which the wire is fed by the feeding means between the support rollers a distance which is adjustable to permit regulating the curvature of bending and consequently the diameter of the coils, the outside perimeter of the bending roller being equal to the perimeter of the formed coils, the last-mentioned perimeter being determined by said distance, whereby a helical winding having a straight axis of winding is obtained.

7. A device for obtaining a helical winding of a metal wire, which winding comprises coils that are inclined relative to the axis of winding and offset from each other, said device comprising means for feeding the wire longitudinally, two support rollers which are in facing relation to each other on both sides of the wire fed by the feeding means, and a rotary bending roller having an axis of rotation which is located within the bending roller and is eccentric relative to the center of the bending roller and offset in a fixed position relative to the path in which the wire is fed by the feeding means between the support rollers a distance which is adjustable to permit regulating the curvature of bending and consequently the diameter of the coils, the outside perimeter of the bending roller being different from the perimeter of the formed coils, whereby a helical winding having a curved axis of winding is obtained.

8. A device for obtaining a helical winding of a metal wire, which winding comprises coils that are inclined relative to the axis of winding and offset from each other, said device comprising means for feeding the wire longitudinally, two support rollers which are in facing relation to each other on both sides of the wire fed by the feeding means, and a rotary bending roller having an axis of rotation which is within the bending roller and is eccentric relative to the center of the bending roller and offset in a fixed position relative to the path in which the wire is fed by the feeding means between the support rollers, the plane of the bending roller being axially offset from the plane in which the wire is fed by the feeding means through the support rollers, whereby a helical winding is obtained whose coils have planes which are inclined relative to each other, that is a helical winding that has a toric envelope.

9. A device for obtaining a helical winding of a metal wire, which winding comprises coils that are inclined relative to the axis of winding and offset from each other, said device comprising means for feeding the wire longitudinally, two support rollers which are in facing relation to each other on both sides of the wire fed by the feeding means, and a rotary bending roller having an axis of rotation which is located within the bending roller and is eccentric relative to the center of the bending roller and offset in a fixed position relative to the path in which the wire is fed by the feeding means between the support rollers and said axis of rotation being so located relative to each other that the feeding means and support rollers feed the wire against the periphery of the bending roller so that the wire is bent thereby, the radius of curvature of the bend produced in the wire being a function of the radial distance between the point of contact of the wire on the periphery of the bending roller and said axis, said distance varying progressively as the bending roller rotates about said axis as the bending of the wire proceeds, the perimeter of the bending roller being different from the perimeter of the formed coils and the plane of the bending roller being axially offset from the plane in which the wire is fed by the feeding means through the support rollers, whereby a helical winding is obtained which has a curved axis of winding and whose coils have planes which are inclined relative to each other.
